APPARATUS FOR PERFORATING BANDS OF
CELLULOSE FOIL, METAL FOIL, AND THE
LIKE

Adolf Rambold, Dresden-Laubegast, Germany

Original application August 8, 1935, Serial No.
35,390. Patent No. 2,101,753. Divided and this
application January 14, 1937, Serial No. 120,568.
In Germany September 17, 1934

11 Claims. (Cl. 164—99)

This invention relates to apparatus for perforating bands of cellulose foil, metal foil and the like, and is a division of my application for Method of and apparatus for producing perforations of small diameter in bands of cellulose foil, metal foil and the like, filed August 8, 1935, and bearing the Serial Number 35,390.

The problem of perforating bands of cellulose foil, metal foil or the like by means of machinery has not yet been satisfactorily solved. For example, the attempt to employ a roller fitted with steel pins as a perforating tool has proved unsuitable on account of the costs and also the technical difficulties. The wear of the pins is excessive as may be appreciated from the fact that in the case of a roller about 150 mm. wide 60 pins disposed in one row all act at once and the total power flux is distributed upon a very small area. This produces too great a strain on the band of material itself and the perforation is not satisfactory and uniform, particularly in the case of small perforations of from $\frac{1}{2}$ mm. diameter downwards. There is also considerable waste of time, since the loss of one pin is sufficient to put the tool out of action.

A perforating machine is known (U. S. Patent No. 1,967,202 to Dalton) with means for feeding and unwinding a strip of material and having a perforating punch operated by an eccentric and actuating wheels provided with a plurality of perforating needles, the wheels operating simultaneously and on a comparatively small area, the speed of the punch motion being greater than that of the work motion. This machine, however, discloses considerable inconveniences as compared to that of the present application, inasmuch as the mass moved is much greater, even though it is attempted to balance the mass forces by counterweights. Furthermore, the stress to which the material is subjected in the course of the perforation is too considerable, and, which is no less important, this machine cannot form a perfect perforation, which the machine as disclosed in the application safely forms, owing to its bevel ground cutting tools. The machine, according to the present application, is capable of much faster operation, just as a steam turbine rotates much faster than the fly-wheel of a piston steam-engine.

The results obtained with stamping tools have also proved unsatisfactory, since in practice these permit of only small feed movements. These tools were, furthermore, much too weak and delicate for such small holes and therefore too sensitive.

As distinct from these previous attempts, the present invention makes it possible to effect the required perforation satisfactorily in a very short time and at little cost.

According to the invention, a plurality of perforating wheels, relatively displaced in stepped formation (in the form of a staircase) are employed for effecting the perforation, so that the tools are distributed over the longest possible stretch of the band for a given hole spacing.

Furthermore, it is of importance that the cutting edges of the individual cutting tools are ground back.

An embodiment of apparatus in accordance with the invention is illustrated diagrammatically in the accompanying drawing by way of example.

Fig. 1 is a side elevation of the apparatus.

Fig. 2 is a fragmentary plan view, partly in section, corresponding to Fig. 1.

Fig. 3 shows part of a cam means hereinafter described.

Fig. 4 shows the disposition of the perforating tools on one of the tool holders, their clamping disc being omitted.

Fig. 5 illustrates a known form of cutting tool.

Fig. 6 shows a novel cutting tool in side elevation.

Fig. 7 is a front view of the new cutting tool.

Fig. 8 shows a perforation as made with the known tool.

Fig. 9 shows a perforation as made with the new tool.

In the drawing, 1 indicates a cylinder which has a sleeve or covering 2 of hard rubber or the like. 3 is a reel of cellulose foil to be perforated, 4 a tensioning roller for the band 8 of the cellulose material, 5 a pair of pull-rollers, and 6 a take-up roller for the perforated material. The take-up roller is rotatably carried by arms pivotedly mounted at 7.

The band of material 8 passes over the cylinder 1 which is fixed on its shaft 26. Grouped about the cylinder 1 are tool holders 9, these being successively offset in stepped formation across the cylinder and thereby, as shown in Fig. 2, distributed with a certain space in the direction of the width (as at a) and in axial direction (as at b). The tool holders are distributed over as great a width of the work as possible within the limits of the width of the drum 1, and in radial as well as axial direction, which may be done by changing the space b, the punches being shiftably arranged. Each holder 9 is constituted by a bush which is keyed or clamped on a shaft 10 disposed

in a tubular guide 11. The guide has webs 12 which engage, after the manner of a saddle, a guide member 14 fixed to the machine frame 13. The members 12 and 13, 14 are pivotally interconnected by a pin 15, so that the guide 11 and holder shaft 10 can be rocked to move the perforating tools carried by the holder 9 towards or away from the cylinder 1. A spring 16 fixed to the frame 13 and to the guide 11 tends to press the holder 9 to the cylinder. The penetration depth of the punches into the work may be regulated by means of a set-screw 17 shiftable with regard to a stop 18 of the guide member 14.

The lateral axial spacing of the individual tool holders may be varied by interposing rings (not shown).

As shown in Fig. 4, each bush-shaped holder 9 presents a ring surface 19 having radial grooves in which the perforating tools 20 are fitted. The tools 20 are centered by a screw bolt 21 (Fig. 2) and are firmly clamped to the holder by a disc 22 engaged by a nut 23 threaded on the bolt 21, to form a perforating wheel rotatable with the shaft 10.

The other end of each shaft 10 carries a pinion 24 which meshes with a gear 25 secured to the shaft 26 of the cylinder 1. Loosely mounted by the side of the pinion 24 on each shaft 10 is a cam roller 27 which engages a cam disc 28 (Fig. 3). Preferably this cam disc is disposed in the gear casing 29 which is fitted with a handle 30.

As already mentioned, the cutting tools in each holder 9 are radially disposed and form a perforating wheel, which rotates around its axis, that is about the axis of its shaft, no relative motion taking place between the perforating wheel and the work to be perforated by motion of the latter and simultaneous rotation of the perforating wheel about its axis.

If a cutting tool 31 (Fig. 5) of circular section having a cutting edge 33 plane ground at right angles to its longitudinal axis were used, satisfactory perforation would not be obtained with the apparatus described, because of the manner in which the tool is applied to the work. Manifestly, at the beginning of the cutting or perforating action, the tool is applied to the work 34 in such a way that it increasingly penetrates into the work, but at the end it is again lifted off; consequently, a cutting tool with a cutting edge as stated is unable to produce a clean and complete cut. Usually the cut away piece 36 (Figs. 5 and 6) forming the perforation 35 remains hanging on the work.

For this reason, and in accordance with the invention, the cutting edge of each tool 20 (Figs. 6 and 7) is ground back, whereby it becomes possible to produce a satisfactory cut; moreover, the tool is recessed, as by grinding, transversely to the cutting direction so that the cutting edge 32 is obtained. The punches 20 are ground to a bevel transversely to the cutting direction in such a manner that the thus formed points of the cutting needles are arranged in a plane vertical with regard to the axis of the rollers. With such tools, perfect perforation as denoted by 37 in Fig. 9 is attained.

The operation of the apparatus is as follows:— The band of material 8 is pulled off the reel 3 over the tensioning roller 4 and the cylinder 1 by the pull rollers 5 and wound upon the take-up roller 6. In its passage over the cylinder 1 the band 8 is engaged by tools carried by the holders 9 and is perforated. The tool holders, as has

been mentioned above, are positively rotated. The depth of penetration of the tools into the band of material may be accurately adjusted with the aid of the adjusting screw 17 in cooperation with the spring 16. In order that all tool holders may be thrown out of action at once, the engagement and disengagement device comprising the cam rollers 27 and the cam disc 28 is provided. For its operation it is only necessary to displace the lever 30 slightly so as to bring the crests of the cam disc into engagement with the rollers 27, as the two openings coordinated to a roller 27 have a different distance from the center of the cam roller.

In order that the band of material 8 may always be guided in a tensioned condition over the cylinder 1, the pair of rollers 5 is positively driven at a speed of rotation which is slightly greater than that of the cylinder 1.

I claim:

1. In apparatus for producing small perforations in bands of thin cellulose, metal foil and the like, a frame, a band supporting cylinder journaled in said frame and having an elastic surface to provide a resilient backing for said bands, rotatable tool holders spaced side by side around a segment of said cylinder with their axes parallel to the axis of the cylinder, a rotary punching wheel supported by each tool holder, said wheels being offset from each other longitudinally of the cylinder, and means operatively connecting the wheels and cylinder to rotate them in unison.

2. In apparatus for producing small perforations in bands of thin cellulose, metal foil and the like, a frame, a band supporting cylinder journaled in said frame and having a yieldable surface, rotatable tool holders spaced side by side around a segment of said cylinder with their axes parallel to the axis of the cylinder, a rotary punching wheel supported by each tool holder, said wheels being offset from each other longitudinally of the cylinder, and means operatively connecting the wheels and cylinder to rotate them in unison, said punching wheels each having a series of peripherally disposed cutters hollow ground transversely to the cutting direction.

3. In apparatus for producing small perforations in bands of thin cellulose, metal foil and the like, a frame, a band supporting cylinder journaled in said frame and having an elastic surface to provide a resilient backing for said bands, rotatable tool holders spaced side by side around a segment of said cylinder with their axes parallel to the axis of the cylinder, a rotary punching wheel supported by each tool holder, said wheels being offset from each other longitudinally of the cylinder, guide means for said tool holders rockingly supported on said frame to move the wheels toward and from the cylinder, means to adjust the positions of said guide means independently, and means operatively connecting the wheels and cylinder to rotate them in unison.

4. In apparatus for producing small perforations in bands of thin cellulose, metal foil and the like, a frame, a band supporting cylinder journaled in said frame and having a yieldable surface, rotatable tool holders spaced side by side around a segment of said cylinder with their axes parallel to the axis of the cylinder, a rotary punching wheel supported by each tool holder, said wheels being offset from each other longitudinally of the cylinder, guide means for said tool holders rockingly supported on said frame

5 to move the wheels toward and from the cylinder, means to adjust the positions of said guide means independently, and means operatively connecting the wheels and cylinder to rotate them in unison, said punching wheels each having a series of peripherally disposed cutters hollow ground transversely to the cutting direction.

10 5. In apparatus for producing small perforations in bands of thin cellulose, metal foil and the like, a frame, a band supporting cylinder journaled in said frame and having a yieldable surface, rotatable tool holders spaced side by side around a segment of said cylinder with their axes parallel to the axis of the cylinder, a rotary 15 punching wheel supported by each tool holder, said wheels being offset from each other longitudinally of the cylinder, guide means for said tool holders rockingly supported on said frame to move the wheels toward and from the cylinder, an abutment fixed on said frame in the paths of said guide means, an adjusting screw carried by each guide means to engage said abutment and limit movement of the wheel toward said cylinder, springs urging said screws into engagement with said abutment, and means 20 operatively connecting the wheels and cylinder to rotate them in unison.

25 6. In apparatus for producing small perforations in bands of thin cellulose, metal foil and the like, a frame, a band supporting cylinder journaled in said frame and having a yieldable surface, rotatable tool holders spaced side by side around a segment of said cylinder with their axes parallel to the axis of the cylinder, a rotary 30 punching wheel supported by each tool holder, said wheels being offset from each other longitudinally of the cylinder, guide means for said tool holders rockingly supported on said frame to move the wheels toward and from the cylinder, an abutment fixed on said frame in the paths of said guide means, an adjusting screw carried by each guide means to engage said abutment and limit movement of the wheel toward said cylinder, springs urging said screws into engagement 35 with said abutment, and means operatively connecting the wheels and cylinder to rotate them in unison, said punching wheels each having a series of peripherally disposed cutters hollow ground transversely to the cutting direction.

40 7. In apparatus for producing small perforations in bands of thin cellulose, metal foil and the like, a frame, a band supporting cylinder journaled in said frame and having an elastic surface 45 to provide a resilient backing for said bands, rotatable tool holders spaced side by side around a segment of said cylinder with their axes parallel to the axis of the cylinder, a rotary punching wheel supported by each tool holder, said wheels 50 being offset from each other longitudinally of the cylinder, each of said wheels comprising a radially grooved bushing having cutting tools mounted in said grooves and a clamping disc coacting with the bush to hold the cutters in place, and means operatively connecting the wheels and cylinder to rotate them in unison.

55 8. In apparatus for producing small perforations in bands of thin cellulose, metal foil and the like, a frame, a band supporting cylinder 60 journaled in said frame and having a yieldable

surface, rotatable tool holders spaced side by side around a segment of said cylinder with their axes parallel to the axis of the cylinder, a rotary punching wheel supported by each tool holder, said wheels being offset from each other longitudinally of the cylinder, each of said wheels comprising a radially grooved bushing having cutting tools mounted in said grooves and a clamping disc coacting with the bush to hold the cutters in place, said cutting tools being transversely hollow ground, and means operatively connecting the wheels and cylinder to rotate them in unison. 5

10 9. In apparatus for producing small perforations in bands of thin cellulose, metal foil and the like, a frame, a band supporting cylinder 15 journaled in said frame and having a yieldable surface, rotatable tool holders spaced side by side around a segment of said cylinder with their axes parallel to the axis of the cylinder, a rotary 20 punching wheel supported by each tool holder, said wheels being offset from each other longitudinally of the cylinder, guide means for said tool holders rockingly supported on said frame to move the wheels toward and from the cylinder, 25 means to adjust the positions of said guide means independently, means operatively connecting the wheels and cylinder to rotate them in unison, and means rockingly supported by said frame and engaging said guide means to rock all said guide 30 means simultaneously toward and from the cylinder.

35 10. In apparatus for producing small perforations in bands of thin cellulose, metal foil and the like, a frame, a band supporting cylinder 40 journaled in said frame and having a yieldable surface, rotatable tool holders spaced side by side around a segment of said cylinder with their axes parallel to the axis of the cylinder, a rotary 45 punching wheel supported by each tool holder, said wheels being offset from each other longitudinally of the cylinder, guide means for said tool holders rockingly supported on said frame to move the wheels toward and from the cylinder, an abutment fixed on said frame in the paths of said guide means, an adjusting screw carried by each guide means to engage said abutment and limit movement of the wheel toward said cylinder, springs urging said screws into engagement 50 with said abutment, means operatively connecting the wheels and cylinder to rotate them in unison, and means rockingly supported by said frame and engaging said guide means to rock all said guide means simultaneously toward and from the cylinder. 55

60 11. In apparatus for producing small perforations in bands of thin cellulose, metal foil and the like, a frame, a band supporting cylinder 65 journaled in said frame and having an elastic surface to provide a resilient backing for said bands, rotatable tool holders spaced side by side around a segment of said cylinder with their axes parallel to the axis of the cylinder, a rotary punching wheel supported by each tool holder, and means operatively connecting the wheels and cylinder to rotate in unison, said punching wheels each having a series of peripherally disposed cutters hollow ground transversely to the cutting direction. 70

ADOLF RAMBOLD.
